LIQUID COOLING APPARATUS

Application filed December 27, 1929. Serial No. 416,773.

This invention relates to apparatus for cooling water or other liquids, and has reference more particularly to coolers designed for use of "dry" ices such as exemplified by 5 solidified carbon dioxide.

The chief aim of my invention is to render more practical than heretofore, use of refrigerants of the kind referred to in cooling water and other liquids through provision of 10 a cooling apparatus which is structurally simple, reliable in operation, economic as regards consumption of the refrigerant, and wherein the chilling effect is produced indirectly, i. e. by circulation of the cold free gas sub- 15 limated from the refrigerant around the reservoir containing the liquid undergoing cooling, rather than by direct contact of the refrigerant itself with the reservoir, to the 20 advantage of effectively precluding the possibility of freezing the liquid.

I further aim, in connection with a cooler operative under the above principle, to pre-determine circulation of the refrigerating gas in a direction counter to flow of the liquid 25 in the reservoir, thereby to promote more uniform thermic interchange with corresponding enhancement in the efficiency of the apparatus.

Still other objects and attendant advantages of this invention will be manifest from the detailed description following when considered in connection with the attached drawings, wherein Fig. I is a sectional view of a 30 liquid cooling apparatus conveniently embodying my present improvements.

Fig. II is a plan view of the same.

Fig. III is an elevation of the left hand end 40 of the structure as considered in Fig. I, with parts broken away to better disclose otherwise hidden features; and,

Fig. IV is a view somewhat similar to Fig. I but showing an alternative form of my invention.

With reference first more particularly to 45 Figs. I, II and III of these illustrations, the numeral 5 designates a reservoir which, in the present instance, is made from ceramic material to rectangular configuration. Communicating into the reservoir 5 through a 50 metallic coupling 6, is a bell 7 likewise made

from ceramic material and adapted to receive the mouth of an inverted supply container 8. As shown, the reservoir 5 and the bell 7 are surrounded by an insulate casing generally designated by the numeral 9, the 55 same being formed of cork or other suitable thermo-insulation 10 and protected on the outside by a sheathing 11 of metal. To render the casing 9 gas tight, the joints are all sealed with a suitable cementitious substance 60 as at 12, and a coating of like material applied to the insides of its walls as at 13. At the interior, the casing 9 affords a space 15 above the reservoir 5 for a charge C of solid carbon dioxide, here shown as being in block 65 form, with interposition of insulation at 16 and 17 to prevent direct contact of the refrigerant C with either the reservoir 5 or the bell 7, the insulation 17 being U-shaped in cross-section, as shown in dotted lines in Fig. II, 70 so as to surround said bell. The casing 9 also affords passages 18, 19, 20, 21, 22 along the sides (Fig. III), ends and bottom (Fig. I) of the reservoir 5, as well as a communicating clearance 23 around the bell 7, which 75 clearance leads to the exterior at the top of the structure.

The space 15 for the refrigerant C is accessible through an opening 25 in the top of the casing 9, said opening being closed by a 80 removable plug 26. This plug 26 is constructed from a plurality of layers of felt sewed together by stitching conventionally indicated at 27, and it is liftable by a ring 28 which is secured by means of a clip 29 engaged through an aperture in a sheet metal plate 30 constituting the top of said plug.

The casing 9 is fitted with a cover lid comprising counter part sections 31 which meet along the longitudinal medial plane of the structure as shown in Fig. II, said lid sections having down turned flanges 32 to overlap the sides of the casing 9, and attached angle lugs 33 to prevent their displacement relatively.

Referring to Fig. I, it will be observed that the coupling 6 comprises a tubular nipple 35 which is threaded for engagement by nuts 36, 37, adapted, through interposed washers 38, 39 to compress sleeves 40, 41 of rubber or

the like into liquid tight contact with the sides of apertures 42, 43 respectively provided for the ends of the nipple 35 in the reservoir 5 and the bell 7. The nuts 36, 37 are also instrumental in clamping, between the reservoir 5 and the bell 7, a spacing element having the form of a tripod 45.

Water is drawn from the reservoir 5 under control of a plunger operated faucet 46 attached to the outer end of another tubular nipple 47 which leads horizontally through the side wall of the casing 9. As shown, the nipple 47 has a fluid tight connection at 48 with the reservoir 5 similar in construction 10 to the fluid tight juncture means employed with the coupling 6.

The operation of the cooler is as follows: As the cold heavier-than-air free gas sublimates from the charge C of solid carbon dioxide in the space 15, it descends down 20 along the sides 18, 19 (Fig. II) and left hand end 20 (Fig. I) of the reservoir 5 and then passes horizontally through the passage 22 beneath said reservoir to the passage 21 at 25 the opposite end of the latter. From thence, the gas flows upward into the clearance 23 around the bell 7, and, after being spent, finally escapes at the top of the casing 9 into the outside atmosphere; all as shown by the 30 arrows in Fig. I. The cold gas thus circulates around the reservoir 5 and the bell 7 in a direction counter to the flow of the water in them, thereby cooling the water to a palatable 35 temperature suitable for drinking purposes, the danger of freezing being precluded by avoidance of direct contact of the refrigerant C with either the reservoir 5 or the bell 7 as a consequence of interposition of the insulation at 16 and at 17.

40 In the alternative form of my invention shown in Fig. IV, the bell of the first described form is supplanted by a pipe connection 6a for leading water from a house main directly into the reservoir 5a, said pipe connection entering the casing at the bottom and passing upward through the insulation 10a. The means here employed to insure water tightness at the junctures of the inlet pipe 6a and the drain pipe 47a with the reservoir 45 5a are identical to those described in connection with the first embodiment. In the present instance, escape of the spent refrigerating gas takes place through a small duct 23a that extends up through the insulation from the top of the passage 21a at the right hand end of the reservoir 5a. Except for the differences noted, the cooler of Fig. IV is of the same construction as the cooler of Figs. I-III and, moreover, operates under the same principle. In order to obviate the necessity for a separate detailed description, all corresponding parts not specifically referred to have been designated by the same reference numerals previously employed with addition 55 of the subscript "a".

Having thus described my invention, I claim:

1. In liquid cooling apparatus, a closed 70 ceramic reservoir for traverse of the liquid which is to be cooled; and a surrounding thermo-insulating casing providing a superposed space for a charge of solid carbon dioxide with interposition of insulation preventing direct contact of the refrigerant with the top of the reservoir, and communicating passages 75 about said reservoir for the free circulation of the gas sublimated from the refrigerant in a direction counter to the flow of the liquid therein.

2. In liquid cooling apparatus, a reservoir 80 for traverse of the liquid which is to be cooled; and a surrounding thermo-insulating casing providing a space for a charge of solid carbon dioxide, and passages determining 85 circulation of the cold free gas sublimated from the refrigerant around said reservoir in a direction counter to the flow of the liquid therein.

3. In liquid cooling apparatus, a closed 90 reservoir for traverse of the liquid which is to be cooled; a bell communicating into the reservoir and adapted to receive the mouth of an inverted supply container; and a surrounding thermo-insulating casing providing a 95 space for a charge of solid carbon dioxide and continuous passages determining flow of the cold free gas sublimated from the refrigerant around the reservoir and the bell in a direction counter to the flow of the liquid in them.

4. In liquid cooling apparatus, a closed 100 reservoir for traverse of the liquid which is to be cooled; a removable bell communicating into the reservoir by way of a coupling nipple 105 with a fluid-tight connection and adapted to receive the mouth of an inverted supply container; and a surrounding thermo-insulating casing affording a superposed space for a charge of solid carbon dioxide with interposition of insulation preventing direct contact of the refrigerant with either the reservoir or the bell, and passages about said reservoir and bell for free circulation of the gas sublimated from the refrigerant in a direction counter to the flow of the liquid being cooled.

5. In liquid cooling apparatus, a closed 110 reservoir for traverse of the liquid which is to be cooled; a bell communicating into the reservoir and adapted to receive the mouth of an inverted supply container; and a surrounding thermo-insulating casing affording a space for a charge of solid carbon dioxide with interposition of insulation preventing direct contact of the refrigerant with either the reservoir or the bell, and passages determining flow of the cold free gas sublimated from the refrigerant about said reservoir and bell in a direction counter to the flow of the liquid in them.

6. In liquid cooling apparatus, a closed 120

reservoir for traverse of the liquid which is to be cooled, a bell communicating into the reservoir and adapted to receive the mouth of an inverted supply container; and a surrounding thermo-insulating casing affording a space for a charge of solid carbon dioxide, passages around the reservoir for circulation of the cold free gas sublimated from the refrigerant, and a communicating clearance around the bell for escape of the gas to the exterior of the refrigerator.

7. In liquid cooling apparatus a closed ceramic reservoir for traverse of the liquid which is to be cooled; a ceramic bell communicating into the reservoir through a metallic coupling and adapted to receive the mouth of an inverted supply container; and a surrounding thermo-insulating casing affording a space for a charge of solid carbon dioxide, and passages about said reservoir and bell for circulation of the cold free gas sublimated from the refrigerant.

8. In liquid cooling apparatus, a closed reservoir for traverse of the liquid which is to be cooled; an inlet leading into the reservoir; and a surrounding thermo-insulating casing providing a space for a charge of solid carbon dioxide, and communicating passages determining flow of the cold free gas sublimated from the refrigerant around the reservoir and the inlet in a direction counter to the flow of liquid in them.

9. In liquid cooling apparatus, a closed ceramic reservoir for traverse of the liquid which is to be cooled; a similar material bell communicating into the reservoir and adapted to receive the mouth of an inverted supply container; and a surrounding thermo-insulating casing providing a space for a charge of solid carbon dioxide with interposition of insulation above and out of direct contact with the reservoir, and continuous passages about the reservoir and the bell for circulation of the cold free gas sublimated from the refrigerant.

In testimony whereof, I have hereunto signed my name at Philadelphia, Pennsylvania, this 23rd day of December, 1929.

CHARLES E. BONINE.
